UNITED STATES PATENT OFFICE.

CURTIS CLARK MYERS, OF CINCINNATI, OHIO.

INCINERATOR.

1,160,437.

Specification of Letters Patent. Patented Nov. 16, 1915.

Application filed May 24, 1915. Serial No. 30,065.

To all whom it may concern:

Be it known that I, CURTIS CLARK MYERS, a citizen of the United States, and residing at Cincinnati, in the county of Hamilton 5 and State of Ohio, have invented a new and useful Improvement in Incinerators, of which the following specification is a full disclosure.

My invention relates to incinerators for domestic purposes in consuming decayable waste or refuse in a sanitary, economical, and convenient manner.

An object of the invention is to provide a combustion chamber in which the garbage 15 waste will be incinerated by surroundingly subjecting it to the intense heat from direct and indirect action of the flame, including an entrainment of air and vapor to and from the mass for complete and rapid combustion.

Another object is to provide a combustion chamber having alternate gas conduits and smoke flues providing flame jets and vent ports throughout its entire height.

Another object is to provide a combustion chamber having a high temperature fire zone combined with provisions for causing all smoke and distilled gases to pass therethrough before entering the stack.

A further object deals with the distribution of the fuel supply to create the high temperature fire zone.

Another object is to provide means for protecting the flame jet openings and smoke ports, formed to provide a water shed therefor, and to provide an unobstructed passageway between the flame jet openings and the smoke ports.

Another object is to provide a central 45 burner at the base of the combustion chamber provided with a perforated protecting hood, serving to radially direct the flame of said burner across the lower portion of the combustion chamber.

Another object is to provide an unobstructed vent leading from the ash-pit direct to the stack and independent from the combustion chamber.

Other objects deal with the construction 50 of the combustion chamber, the grate mechanism and the arrangement of fuel manifolds, all of which will be described in detail in the following description of the accompanying drawings, forming a part of this specification, and in such drawings like

characters of reference designate corresponding parts throughout the several views of which—

Figure 1 is a central vertical section. Fig. 2 is a front elevation, partly broken away to show the interior details. Fig. 3 is a plan section on line 3—3, Fig. 1. Fig. 4 is an enlarged perspective view of one end of one of the gas flue partition plates. Fig. 5 is a plan section on line 5—5, Fig. 1. Fig. 6 is a plan section of the center gas burner on line 6—6, Fig. 1.

The principle of the invention as an organized incinerator is to wholly surround the garbage mass with flame and sufficient air to make complete combustion of the garbage mass possible; and to provide a high temperature or maximum combustion zone with sufficient air at a selected portion of the chamber, through which all gases must pass and be completely consumed, before entering the flue to stack.

To this end, two independent sources of combustion are provided, a central base burner and a series of burner orifices around the sides of the chamber from the bottom to the top, selectively alternating with smoke escape vents, whereby the smoke escapes at the several points of combustion, within centrally and vertically or laterally and upwardly exterior of the mass, being united in said maximum combustion zone so as to be completely consumed before passing out of the incinerator.

The rear portion of the base section 1 is of semi-circular contour, the front portion being extended to rectangular formation, providing a plane front surface, having a plurality of burner apertures therein. The ash-pit floor is removably supported at the bottom of the base section and supports the ash-pan 2, which is removable through a lateral opening 3, said opening being closed by a hinged door 4.

The inner or main casing consists of a lower section 5 bolted to the base section 1 and an upper section 6 bolted to the lower section, having a stack 7 leading from the top, and a garbage receiving aperture in the front wall thereof.

Secured to the base section and to the main casing is a front plate 8, provided adjacent the aperture in the upper section 6 with a swinging chute door 9 pivoted to the front plate and having inwardly pro-

105

110

jecting side plates 10, which, when the door is open, serve as sides of a garbage receiving hopper. Secured to the top of the upper section 6 is a top plate 11 provided with 5 an aperture through which the stack 7 projects, said aperture being larger than the stack to provide a vent opening 12.

Surrounding and spaced apart from the main casing is an outer heat insulating casing 13, which is formed of two pieces of sheet metal and a filler of non-conductive material, such as asbestos. This casing is secured to the base section, the front plate 8 and the top plate 11.

15 To prevent excessive heating of the main and outer casings, I provide means for causing a current of heat insulating air to circulate between them and escape through the vent opening 12 in the top plate. To this end, one or more openings 15 are formed 20 near the lower edges of the front plate 8 and the outer casing 13.

The combustion chamber is formed of a series of alternate gas conduits and smoke 25 flues 20 and 30 secured together by screws 14. Each of the smoke flues 30 rests on and is secured to radial wings 40 of a supporting spider or grid 41, which in turn rests on a series of lugs 42, projecting inwardly from the base section 1. The grid 41 is provided with spaced notches 43 in its periphery which, when said grid is slightly rotated, register with the supporting lugs 42, thereby permitting a removal 30 of the combustion chamber unit through the base section, after which any individual flue 35 may be separately detached.

While I have described the relative disposition of the gas conduits and smoke flues 40 as being alternate, the term "alternate" is intended to include all variations in the specific arrangement of these elements which conform to the broad principle of providing a group of vertically disposed flame jets relatively spaced around the combustion chamber and flanked on either side by smoke flues to carry off the products of combustion, it making no effective difference whether two smoke flues separate the gas conduits or two 50 gas conduits separate the smoke flues, providing they are of proper relative sizes.

Secured to the upwardly extended outer walls of the smoke flues 30 is a circular dished baffle plate 44, the purpose of which 55 will hereinafter be described. The forward half of said plate fits closely to the main casing, so as to prevent the incoming garbage falling in the space between said casing and the combustion chamber, the periphery of the rear half being provided with notches 45, registering with said space. This space being in direct communication with the ash-pit provides an unobstructed 60 direct vent for all ash-pit fumes and prevents any possibility of explosions therein in

the event of the smoke flues becoming obstructed. The gas conduits 20 are provided with a series of inwardly projecting lips 21 and gas jet openings 22 below each lip to direct a series of flame jets radially toward the center of the combustion chamber. The lips serve to prevent the gas jet openings from becoming clogged and to provide an unobstructed horizontal passage to the adjacent smoke flues 30, which are likewise provided with similar lips 31. Below each of the lips 31 is a smoke port 32, having a beveled upper edge to accelerate the passage of smoke and gases therethrough.

The lips 21 of the gas conduit 20, and the 80 lips 31 of the smoke flues 30 also form a protecting water-shed for their companion gas jets and ports.

Within each gas conduit 20, I provide a partition plate 23, extending from a point 85 below the lowermost gas jet opening 22, upwardly through the major portion of the conduit and terminating at the ends with a circular ring, (see Fig. 4), which serves to retain the plate in normal position.

90 These plates divide the gas supply to insure an even distribution thereof to all of the jets 22, excepting those near the top of the conduit which receive a slight excess supply to provide a high temperature fire 95 zone at the top of the combustion chamber.

The smoke flues 30 are open at the top and bottom to afford an unobstructed draft therein. Each of the gas conduits 20 extend below the grid 41 and are connected to one 100 of a pair of semi-circular gas manifolds 24 which are supplied with gaseous fuel by conductor pipes 25, having suitable mixing attachments and regulator valves 26 at their base entrance.

105 The central gas burner is composed of two sections 50 and 51, being perforated to provide a circular series of flame jets. The lower section rests on the grid 41 and is provided with a downwardly projecting gas 110 conduit 52, which projects through an aperture in the grid and is connected to a conductor pipe 53, provided with a mixer attachment and valve 54 similar in form to those described in connection with the gas 115 flues 20. The burner section 50 intermeshes with the section 51 and is provided with a semi-circular baffle ring 55, from the central portion of which protrudes a tongue 56 extending downwardly into the gas conduit 52 120 of the lower section 51, see Fig. 6. This baffle ring and tongue serve to divide the gas supply to promote an even distribution thereof to the burner.

125 Resting on the grid 41 and surrounding the central burner is a cone-shaped hood 57, which protects the burner and directs the flame thereof radially through horizontal apertures 58 in the cone. The lower walls of these apertures are slightly inclined 130

downwardly and outwardly to prevent any moisture contained in the garbage from flowing into the cone and onto the burner.

The grate consists of four sector shaped grate sections 60 which are detachably secured, in an inwardly and downwardly inclined position, to a vertically movable grate spider 61 which is slidably supported on a stud 62 fixed to and projecting downwardly from the center of the grid 41. The arms of the spider 61 have forked ends 63, which extend upwardly on either side of the radiating grid arms or spokes and each end 63 is connected by a tie-bar 64 to the adjacent end 63 of the next spider arm. Between the ends of the grate sections 60, the radiating grid spokes are provided with inwardly inclined beveled faced filler lugs 65, which fill in the space between the grate plates to form, in effect, a continuous inclined circular grate surface.

The means employed for lowering the grate consists of a forked lever 70, which is secured to a rock shaft 71 journaled on the front wall of the base section 1 and operated by a hand lever 72 external thereof. The lever 70 is slotted at its inner forked ends to engage trunnions 73, formed on the extended sleeve 74 of the grate spider 61. The hand lever 72 is provided with suitable latch mechanism to lock the grate mechanism in normal position.

I will now describe the general operation of the device shown, although it is to be understood that the invention is not to be limited thereto, as it is obvious that many other specific forms may be designed without departing from the broad underlying principles involved.

In practice, the preliminary drying out of the usually more or less wet garbage while it is accumulating in the incinerator, is quickly effected by the circulation of air currents through the garbage mass. These air currents are directed upwardly through the cone apertures 58 and pass radially and upwardly through the garbage mass up through the stack while others are directed through the smoke flues 30, creating a draft therein to draw the moisture through the smoke ports 32. Thus the drying out process is expedited by the surrounding of the garbage mass by circulating air currents and by directing other air currents through the central portion thereof. Likewise, during the incinerating process, the garbage mass is surrounded throughout its entire height by the smoke flue ports through which the smoke and distilled gases are drawn by the air currents in the smoke flues. Each of these smoke ports is disposed closely adjacent to one of the gas jet openings 22 of the gas conduits 20, thus providing smoke vents distributed over the entire exterior surface of the garbage mass and immediately

adjacent the zone of combustion of each individual flame jet. With this arrangement the distilled gases and smoke pass beneath the lips 21 and 31 and immediately through the smoke ports and into the smoke flues 30.

The partitions 23 in the gas conduits 20 control the gas supply to create a high temperature zone across the top of the combustion chamber and following the correct principles of perfect combustion (passing the products of combustion through the hottest part of the fire) the smoke and gases are directed by the dished baffle plate 44, inwardly and downwardly through the high temperature zone before passing off through the stack, thereby affording complete combustion and eliminating all obnoxious odors.

Having described my invention, I claim:

1. A device of the nature described comprising a combustion chamber having a series of alternate perforated gas conduits and ported smoke flues distributed in vertical parallelism around the entire circumference thereof, and means for conveying fuel to the gas conduits.

2. A device of the nature described comprising a combustion chamber having a plurality of alternate perforated gas conduits and ported smoke flues distributed in vertical parallelism around the entire circumference and extending the full height thereof, and means for conveying fuel to the gas conduits.

3. A device of the nature described comprising a combustion chamber formed of a series of alternate perforated gas conduits; and ported smoke flues detachably united and distributed in vertical parallelism around the entire circumference thereof, and means for conveying fuel to the gas conduits.

4. A device of the nature described comprising a combustion chamber formed of a series of alternate perforated gas conduits and ported smoke flues detachably united and distributed in vertical parallelism around the entire circumference and extending the full height thereof, and means for conveying fuel to the gas conduits.

5. A device of the nature described comprising a combustion chamber having a plurality of perforated gas conduits and a plurality of ported smoke flues distributed in vertical parallelism around the circumference thereof, means for conveying fuel to the gas conduits, and means for controlling the fuel supply within the conduits to produce a relatively high temperature fire zone across the upper portion of the combustion chamber.

6. A device of the nature described comprising a combustion chamber having a plurality of perforated gas conduits and a plurality of ported smoke flues distributed in vertical parallelism around the circumfer-

- ence thereof, means for conveying fuel to the gas conduits, means for controlling the fuel supply within the conduits to produce a relatively high temperature fire zone across the upper portion of the combustion chamber, and a baffle plate adjacent the upper ends of the smoke flues for directing the products of combustion emitting therefrom, through the high temperature fire zone.
10. 7. A device of the nature described having a combustion chamber comprised of a series of perforated gas conduits, a series of ported smoke flues, and a baffle plate adjacent the upper ends of the smoke flues for diverting the products escaping from said flues downwardly toward the center of the combustion chamber, all detachably united to form a unitary structure, and means for conveying fuel to the gas conduits.
15. 8. A device of the nature disclosed comprising a circumferential series of conduits forming an intermediate combustion chamber, the conduits alternately providing gas burners jetting into the chamber and flues for the escape of products from said chamber.
20. 9. A device of the nature disclosed comprising a circumferential series of conduits forming an intermediate combustion chamber, the conduits alternately providing gas burners jetting into the chamber and flues for the escape of products from said chamber, a casing providing a receiving chamber above said combustion chamber, and means intervening said chambers guarding the exit ends of said conduits and directing the products escaping therefrom into the combustion chamber.
25. 10. A device of the nature described comprising a combustion chamber, having flame jet openings and smoke ports distributed throughout the full height and around the entire inner periphery thereof, means for conveying fuel to the flame jet openings, and separate means for conveying the products of combustion entering the smoke ports, to the top of the combustion chamber.
30. 11. A device of the nature described comprising a combustion chamber, having flame jet openings and smoke ports distributed throughout the full height and around the entire inner periphery thereof, means for conveying fuel to the flame jet openings, separate means for conveying the products of combustion entering the smoke ports to the top of the combustion chamber, a burner at the base of the combustion chamber for directing a column of flame upwardly through the center thereof, and means for conveying fuel to the burner.
35. 12. A device of the nature described comprising a combustion chamber, having flame jet openings and smoke ports distributed throughout the full height and around the entire inner periphery thereof, means for conveying fuel to the flame jet openings, and guards protecting said ports.
40. 13. A device of the nature described comprising a combustion chamber having a series of alternate perforated gas conduits and ported smoke flues distributed in vertical parallelism around the entire circumference thereof, means for conveying fuel to the gas conduits, and a series of lips projecting inwardly from the wall of the combustion chamber above each gas conduit perforation and above each smoke flue port, and having downwardly and inwardly inclined upper surfaces.
45. 14. A device of the nature described comprising a combustion chamber having a series of alternate perforated gas conduits and ported smoke flues distributed in vertical parallelism around the entire circumference thereof, means for conveying fuel to the gas conduits, a series of lips projecting inwardly from the wall of the combustion chamber above each gas conduit perforation and above each smoke flue port, and having downwardly and inwardly inclined upper surfaces, a burner at the base of the combustion chamber, means for conveying fuel to the burner and a conical apertured hood surrounding said burner, the lower wall of said apertures being inclined outwardly and downwardly.
50. 15. In a device of the class disclosed, a circumferential series of conduits forming a combustion chamber, and alternately providing gas burners jetting into the chamber and exit flues communicating with said chamber through apertures longitudinally of said flue conduits, and a gas burner at the base of said chamber.
55. 16. In a device of the class disclosed, a circumferential series of conduits forming a combustion chamber, and alternately providing gas burners jetting into the chamber and exit flues communicating with said chamber through apertures longitudinally of said flue conduits, a gas burner at the base of said chamber, and an apertured conical guard over said base burner.
60. 17. A device of the nature disclosed comprising a series of conduits forming a combustion chamber, and providing gas burners and exit flues communicating with said chamber, through ports in said conduits longitudinally, and guards protecting said ports.
65. 18. A device of the nature described comprising a base section forming an ash-pit, a grid supported thereby and having a plu-

rality of radiating spokes, a combustion chamber supported by the grid, a vertically movable grate consisting of a plurality of grate sections positioned intermediate the grid spokes and normally projecting above said spokes, a grate spider supporting the grate sections in an inwardly and downwardly inclined position, and means for moving the grate.

19. A device of the nature described comprising a base section forming an ash-pit, a grid supported thereby and having a plurality of radiating spokes, a combustion chamber supported by the grid, a burner resting on the grid, a protecting hood surrounding said burner, a vertically movable grate consisting of a plurality of sector shaped grate sections normally projecting above the grid intermediate the hood and the combustion chamber wall, in an inwardly and downwardly inclined position between the grid spokes, their inner edges extending below and inwardly of the outer periphery of the hood, a grate spider supporting the grate sections, and means for vertically moving the grate.

20. In a device of the class described, a combustion chamber, a gas burner at the base thereof, a vent for the products of combustion above such member, means for supplying fuel gas around the sides of said

chamber and from the bottom to the top thereof, providing a maximum combustion zone in the upper portion of said chamber, outlet means for escaping products of combustion around the sides of said chamber and from the bottom to the top thereof, and means directing the products of combustion escaping around the sides of said chamber into said maximum combustion zone in the upper portion of said chamber.

21. In a device of the class described, a casing forming superposed communicating receiving and combustion chambers, conduits within and spaced from said casing longitudinally of the combustion chamber, said conduits providing gas burners jetting into said combustion chamber and exit flues independent of the gas burners communicating with said combustion chamber, a baffle plate intermediate of said chambers and over said exit flues for directing the products escaping from said flues into said combustion chamber, and a gas burner at the base of said combustion chamber.

In witness whereof, I hereunto subscribe my name, as attested by the two subscribing witnesses.

CURTIS CLARK MYERS.
